[57] **CLAIM**

The ornamental design for a hand-powered nail driver, as shown and described.

DESCRIPTION

FIG. 1 is an exploded top perspective view of the hand-powered nail driver showing our new design;

FIG. 2 is a front elevational view thereof, the rear view being a mirror image;

FIG. 3 is a side elevational view thereof, the opposite side being substantially a mirror image thereof;

FIG. 4 is a top plan view thereof;

FIG. 5 is a bottom plan view thereof.

FIG. 4

FIG. 5

FIG. 2

FIG. 3
